UNITED STATES PATENT OFFICE.

GEORGE H. HALLOCK, GEORGE F. FREDERICK, AND BENJAMIN H. PURCELL, OF TERRE HAUTE, INDIANA, ASSIGNEES TO AUTOMATIC MACHINERY COMPANY, OF TERRE HAUTE, INDIANA, A CORPORATION OF INDIANA.

CONVEYER SYSTEM.

Application filed September 15, 1919. Serial No. 323,964.

To all whom it may concern:

Be it known that we, GEORGE H. HALLOCK, GEORGE F. FREDERICK, and BENJAMIN H. PURCELL, citizens of the United States, residing at Terre Haute, in the county of Vigo and State of Indiana, have invented a new and useful Conveyer System, of which the following is a specification.

The object of our invention is to produce an apparatus by means of which articles, such as bottles, jars, cans, packages, etc., may be automatically delivered from one or more stations or sources, to a common carrier, the arrangement being such that the articles from the several sources may be kept from interfering with each other as they pass to and upon the common carrier.

The accompanying drawings illustrate this invention. Fig. 1 is an elevation of one of the lateral feed units, and, in vertical section, the main receiving carrier; Fig. 2 a plan of the parts shown in Fig. 1; Fig. 3 a fragmentary detail of one of the governors; Fig. 4 a section on line 7—7 of Fig. 2; and Fig. 5 a fragmentary plan of a possible arrangement of main receiving carrier and several lateral food units.

The articles are delivered to carrier 15 at various points in its length by feeding carriers 40, which are similar to carrier 15 and each driven by an appropriate motor 41. It is important that, as articles pass any point of receipt, there be no interference with articles arriving at that point. Each carrier 40 delivers toward a side of carrier 15 and the articles are deflected therefrom by deflector-bars 42, 43, so as to pass on to the upper surface of a smooth transfer disk 44 which delivers the articles to carrier 15. As the articles are advanced by disk 44, they come successively into contact with an arm of the star-wheel governor 45 which is moved solely by the articles and is normally locked against movement by a latch-pin 46 engaging ratchet 47 on the governor star obstruc-

ter 45. The lower side of carrier 15 is carried under a sprocket 48 (see Fig. 4) and this sprocket is geared to the shaft of disk 44 (by shaft 40 and gears 50 and 51) so that the movement of disk 44 is synchronized with carrier 15. Angularly adjustable on disk 44 is a cam 52 which intermittently engages roller 53 of lever 54 which carries pin 46 normally restraining the obstruc-

the arrangement being such that, at regular intervals, the governor star obstrucuter 45 is released to permit disk 44 to deliver an article to carrier 15.

Those feed carriers and associated parts will be arranged to deliver from the forming stations to the carrier 15 at appropriate points (as indicated in Fig. 5) and as the disks 44 are synchronized with the carrier 15, it will be apparent that, with proper adjustment, which may be accomplished by angular adjustment of cams 52 and appropriate setting of sprocket wheels 48 in mesh with carrier 15, articles from any particular feed carrier will be deposited on carrier 15 at appropriate spaced intervals which will differ from the points of deposit from any other feed-carrier, and thus the articles will be prevented, as they pass various points of receipt, from interfering with articles arriving at that point.

In order to adapt the device for handling articles of different diameters, the deflector bar 42 is pivoted at 42' and clamped at 42'', while bar 43 is pivoted at 43' and clamped at 43'', so that, as indicated in dotted lines, the throat, or passage, between these two bars may be adjusted to approximately the diameter of the articles arriving on carrier 40 and cause delivery of these articles to a proper point on disk 44 for delivery to governor 45 and carrier 15.

We claim as our invention:

1. The combination with a main conveyer, of a feeding conveyer leading laterally to the main conveyer, a rotary transfer disk arranged in a corner between said conveyers for frictional reception of articles, means for rotating said disk, an obstrucuter arranged adjacent the disk in the line of travel of articles on the disk, means for normally restraining said obstrucuter in obstructing position, and means synchronized with the main conveyer for intermittently withdrawing the restraining means.

2. The combination with a main conveyer, of a feeding conveyer leading laterally to the main conveyer, a rotary transfer disk arranged in a corner between said conveyers for frictional reception of articles, means for rotating said disk, an obstrucuter arranged adjacent the disk in the line of travel of articles on the disk and movable by said articles, means for normally restraining said ob-

stricter in obstructing position, and means synchronized with the main conveyer for intermittently withdrawing the restraining means.

5. 3. The combinaton with a main conveyer, of a feeding conveyer leading laterally to the main conveyer, a rotary transfer disk ar- ranged in a corner between said conveyers for frictional reception of articles, means 10 synchronized with the main conveyer for ro- rotating said disk, an obstricter arranged ad- jacent the disk in the line of travel of articles on the disk, means for normally restraining said obstricter in obstructing position, and 15 means synchronized with the main conveyer for intermittently withdrawing the restraining 55 means.

4. The combination with a main conveyer, of a feeding conveyer leading laterally to the 20 main conveyer, a rotary transfer disk ar- ranged in a corner between said conveyers for frictional reception of articles, means synchronized with the main conveyer for ro- rotating said disk, an obstricter arranged ad- jacent the disk in the line of travel of articles 25 on the disk and movable by said articles, means for normally restraining said ob- stricter in obstructing position, and means synchronized with the main conveyer for in- 30 tervallently withdrawing the restraining 70 means.

5. The combination with a main conveyer, of a feeding conveyer leading laterally to the 35 main conveyer, a rotary transfer disk ar- ranged in a corner between said conveyers for frictional reception of articles, means for rotating said disk, an obstricter arranged in the line of travel of articles from the feeding conveyer to the main conveyer, means for 40 normally restraining said obstricter in ob- structing position, and means synchronized with the main conveyer for intermittently 45 withdrawing the restraining means.

6. The combination with a main conveyer, 45 of a feeding conveyer leading laterally to the main conveyer, a rotary transfer disk ar- ranged in a corner between said conveyers for frictional reception of articles, means for rotating said disk, an obstricter ar- 50 ranged in the line of travel of articles from

the feeding conveyer to the main conveyer, means for normally restraining said obstruc- 60 ter in obstructing position, and means syn- chronized with the main conveyer for inter- mittently withdrawing the restraining 65 means.

7. The combination with a main conveyer, of a feeding conveyer leading laterally to the main conveyer, a rotary transfer disk ar- ranged in a corner between said conveyers for frictional reception of articles, means synchronized with the main conveyer for ro- 60 rotating said disk, an obstricter arranged ad- jacent the disk in the line of travel of articles 65 from the feeding conveyer to the main con- veyer, means for normally restraining said obstricter in obstructing position, and means synchronized with the main conveyer for in- 70 tervallently withdrawing the restraining 75 means.

8. The combination with a main conveyer, of a feeding conveyer leading laterally to the main conveyer, a rotary transfer disk ar- ranged in a corner between said conveyer, 75 for frictional reception of articles, means synchronized with the main conveyer for ro- rotating said disk, an obstricter arranged in the line of travel of articles from the feeding conveyer to the main conveyer, means for 80 normally restraining said obstricter in ob- structing position, and means synchronized with the main conveyer for intermittently 85 withdrawing the restraining means.

9. The combination with a main conveyer, 85 of a feeding conveyer, a rotary transfer disk leading laterally to the main conveyer, a ro- tary star-wheel obstricter arranged in the line of travel of articles from the feeding conveyer to the main conveyer, means for ro- 90 rotating the disk, a pin for normally restraining the obstricter in obstruction position, and a pin withdrawing train driven by the main conveyer.

In witness whereof, we have hereunto set 95 our hands at Terre Haute, Indiana, this tenth day of September, A. D. one thousand nine hundred and nineteen.

GEORGE H. HALLOCK.
GEORGE F. FREDERICK.
BENJAMIN H. PURCELL.
